UNITED STATES PATENT OFFICE.

HENRY KREISINGER, OF PIERMONT, NEW YORK, ASSIGNOR TO COMBUSTION ENGINEERING CORPORATION, OF NEW YORK, N. Y., A CORPORATION OF NEW YORK.

FINELY-DIVIDED-FUEL-BURNING FURNACE.

Original application filed December 13, 1920, Serial No. 430,224. Divided and this application filed September 26, 1924. Serial No. 740,015.

This invention relates to furnaces such as are used for the burning of fuel in finely divided form, as for example in the form of pulverized coal, under stationary boilers.

5 One of the primary objects of my invention is to deliver pre-heated air for combustion into the combustion chamber so as to increase the efficiency of the installation, while at the same time the refractory structure is to be cooled by the pre-heating of the combustion air, i. e. by the absorption of the heat from the refractory structure by combustion air traversing the same before entry into the combustion space.

10 More specifically my invention is directed to a novel form of channelled wall construction by virtue of which the combustion air is heated to a higher degree, and the walls cooled in such manner as to avoid contraction 20 and expansion difficulties.

This application is division of my co-pending application, Serial No. 430,224, filed on Dec. 13th, 1920; issued as Patent No. 1,510,994, October 7th, 1924.

25 Now the foregoing, together with such other objects and advantages as may herein-after appear, or are incident to my invention, are realized, is illustrated in preferred form in the accompanying drawings wherein

30 Fig. 1 is a vertical section through a furnace embodying the invention;

Fig. 2 is a front elevation; and

Fig. 3 is a section taken on the line 3-3 of Fig. 2.

35 Referring now to the drawings the reference character A indicates the furnace or combustion chamber, having an outlet 7 in the upper part thereof, over which is located the boiler 8. Fuel is admitted in powdered form into the upper part of the combustion chamber adjacent the front wall 9 and in a downward direction, through the top or arch 9^a through one or more burners 9^b there preferably being a plurality of these 45 burners arranged in a row. The fuel is admitted with carrying air and additional air is induced through the burner casing, in a manner now well understood in this art. The fuel and flame stream takes a U-shape

50 course through the combustion space, combustion being completed before the tubes of the boiler 8 are reached. Only a portion of the total air required for combustion is supplied with the coal and through the burner, 55 the balance of the air required for combus-

tion being supplied to the combustion space at successive levels, as will be set forth.

The efficiency of the furnace will be greatly increased if a large part of the air for combustion is pre-heated. In the embodiments shown, this is brought about by providing three vertically spaced, horizontally extending channels or compartments 13, 14 and 15 within the walls 9, 10, 11 and 12. The channel 13 begins at the left hand side of Fig. 3 and runs through the side wall 11, the rear wall 10, the side wall 12 and then through the front wall 9, terminating short of the side wall 11. Air flows through the inlet 16 under control of the damper 17 through the channel 13 in the direction of the arrows, and such air in traversing the side wall 11, the rear wall 10, the side wall 12 and the front wall 9 becomes very highly heated indeed before it is introduced into the combustion space through the horizontal row of inlets 18 opening from the channel 13.

55 Inasmuch as there will be some unevenness in the cooling effect by virtue of this long travel of the air, I start the next lowest compartment or channel 14 on the right hand side of Fig. 3, the entering air traversing first the side wall 12 then the rear wall 10, then the side wall 11 and the front wall 9, as indicated by the dotted arrows. In other words, the air flowing through this compartment traverses the walls in the opposite direction from that which flows through the compartment 13. It will be, of course, understood that the compartment 14 has inlets 18 in the front wall for delivering the pre-heated air into the combustion space.

60 The compartment 15 has the air traveling therethrough in the same direction as the case with the compartment 13. If additional compartments be added the flow would be alternately reversed, as just described. By alternately reversing the flow of air through the successive compartments, a more uniform cooling effect is obtained so that the liability of difficulty from uneven expansion and contraction is materially decreased, while at the same time the air will absorb heat to the greatest possible degree thereby enhancing the efficiency to the greatest possible extent. Each compartment being under individual control by the respective dampers 16, any desired regulation may be obtained.

65 It will be noted that a cooling screen of 110

suitably spaced tubes 19 is located in the lower portion of the combustion space, such screen being connected into the circulation of the boiler by downcomers 20 and upcomers 21. The screen has several functions, one of which is to cool the precipitating refuse particles passing therethrough to the point of deposit from out of the fuel and flame stream, to a point below the slagging temperature, so that the deposit will remain readily removable. It will be noted that the headers 22 and 23 are located within the front and rear walls respectively, and these, together with the tubes 19 serve to cool the lower portion of the walls surrounding the combustion space. In this connection, the tubes 19 will perform a large amount of the work performed by the boiler by virtue of their being subjected to radiant heat, by reason of which they abstract large quantities of heat.

Novel effects are also produced on the combustion itself over and above that incident to the supplying of preheated air. While normally there might be a tendency for the inlets nearest the blind end of the compartments to admit more air than the other inlets, the swirling of the air produced at the corner of each compartment at the juncture of the respective side wall and front wall has a tendency to cause more air to flow through the end inlets farthest removed from the blind end of the compartments than would otherwise be the case, and in consequence of this there is a substantial uniformity of delivery through the various inlets. If, however, owing to certain operating conditions, there should be nonuniform flow through a row of inlets conditions will be balanced by the fact that, in the successive compartments, the flow is reversed so that, considered as a whole, practically the

same conditions will be maintained over the space adjacent the front wall.

I claim:

1. A combustion chamber for burning fuel in finely divided form having the wall surrounding the chamber provided with a plurality of vertically spaced horizontally disposed channels extending substantially around the chamber, each channel being blind at one end, with air inlets to the combustion space in the region of the blind end and having an air inlet at the other end, the air inlets for adjacent channels being located adjacent opposite vertical edges of one wall of the chamber and the blind end of each channel being adjacent the air inlet for that channel, whereby the air traverses adjacent channels in opposite directions, and means for admitting the fuel.

2. A combustion chamber for burning fuel in finely divided form in suspension, having an outlet in an upper part, and means for admitting fuel in a downward direction at one side of the combustion chamber so that the fuel and flame stream reverts in U-form, the walls of said chamber being provided with vertically spaced channels extending horizontally substantially around the chamber, each channel being blind at one end, with air outlets into the combustion space in the region of the blind end and having an air inlet at the other end, the air inlets for adjacent channels being located adjacent opposite vertical edges of one wall of the chamber and the blind end of each channel being adjacent the air inlet for that channel, whereby the air traverses adjacent channels in opposite directions.

In testimony whereof, I have hereunto signed my name.

HENRY KREISINGER.
